UNITED STATES PATENT OFFICE.

CHARLES E. SEMPLE, JR., OF YOUNGSTOWN, OHIO.

DIAPHRAGM FOR SOUND REPRODUCERS.

Application filed May 24, 1922. Serial No. 563,441.

To all whom it may concern:

Be it known that I, CHARLES E. SEMPLE, Jr., a citizen of the United States, residing at Youngstown, in the county of Mahoning and State of Ohio, have invented certain new and useful Improvements in Diaphragms for Sound Reproducers, of which the following is a specification.

This invention relates to an improvement in diaphragms for reproducers of phonographs or talking machines, or other sound reproducing devices.

A primary object of the invention is to provide a diaphragm that will give a clear, well defined reproduction of ample volume but without harshness, while at the same time avoiding any tendency to muffle or suppress the sound. To that end the invention has in view a diaphragm that is light in weight, very sensitive, and practically free from sounds resulting from local action of the diaphragm itself.

A further object of the invention is to provide a diaphragm having structural features and characteristics which materially contribute to its proper functioning, comprising a novel distribution and arrangement of reinforcing and absorbing elements designed to prevent the diaphragm from vibrating in partials which, as is well known by those familiar with the operation of reproducers, produces sounds foreign to the record.

A further object of the invention is to utilize appropriate resonant and suberoous materials combined in a manner to effectually overcome many of the difficulties heretofore encountered in diaphragms of the plate type.

With the above and other objects in view which will more readily appear as the nature of the invention is better understood, the same consists in the novel construction, combination and arrangement of parts hereinafter more fully described, illustrated and claimed.

A preferred and practical embodiment of the invention is illustrated in the accompanying drawings, in which:—

Figure 1 is a plan view of the improved diaphragm.

Figure 2 is a cross-sectional view thereof.

Figures 3, 4 and 5 are cross sectional views illustrating modified forms of the diaphragm.

Figures 6, 7, 8 and 9 are also cross sec-

tional views illustrating further modifications of the construction wherein the central part of the diaphragm is of compound formation.

Figure 10 is a diagrammatic view illustrating the formation of partials in the ordinary flat plate type of diaphragm.

Similar reference characters designate corresponding parts throughout the several figures of the drawings.

Diaphragms of the flat plate type, while almost universally used, are open to the objection that they are practically unrestrained in their operation and therefore produce foreign or unrecorded sounds.

By the way of illustration reference may be had to Figure 10 of the drawings which shows a flat plate diaphragm R having connected to the central portion thereof a stylus-bar connecting link S and held at its outer edges between the gaskets T of the reproducer frame. This type of diaphragm may move as a whole, as indicated by the dotted lines x, but it also vibrates in partials, as indicated by the lines y and z, thereby producing the points w of practically no vibration known as nodal points, and the ventral segments w' or points of greatest vibration. The formation of these partials is due to the fact that when the vibration, through the "stylus-bar link connecting member" S, acts on the diaphragm it tends to buckle or depress the area immediately surrounding the center, while the next section of the diaphragm takes a reverse position, etc. to the periphery of the diaphragm. When the diaphragm rebounds a reverse action takes place with reference to the partials, thus forming the diaphragm-generated sounds.

As previously indicated, it is one of the principal objects of the present invention to provide a diaphragm that will tend to avoid the formation of foreign sounds peculiar to itself. To this end the invention contemplates a main diaphragm D which is preferably made of very thin, flexible material that is hard and stiff. In this connection, I have found that materials of a fibrous nature immersed in a bath of resinous material, such as shellac or compounds of shellac and other materials, and allowed to dry and then worked between heated dies is very suitable. That is to say, several sheets of comparatively thin paper, such as tissue paper, may be dipped into a

resinous varnish and allowed to dry and then pressed together between hot plates or dies, which transforms the separate sheets into one unitary structure of the desired thickness. Or, on the other hand, a single sheet of sufficient weight may be used, which, after proper treatment, may be pressed into the desired thickness and form.

In its primary aspect, therefore, the present diaphragm contemplates a main diaphragm D, Fig. 2, comprising a disk of a suitable relatively elastic material in combination with a stiffening plate or reinforcing disk 4 and a ring F of relatively soft or suberous material like cork, the central portion D' of the diaphragm being deflected to one side of the plane of the body thereof to provide increasing stiffness and reinforcement and also to reduce the tendency to vibrate in partials.

Referring now more specifically to Figure 2 of the drawings, it will be observed that the main diaphragm D has its central portion D' pressed into a substantially crowned or offset portion 1, the center of which, adjacent the opening 2, is preferably given a substantially conical form 3. The concave side of the crowned portion is preferably provided with a reinforcing member 4 of the same material as the diaphragm, which gives added strength and reinforcement to that portion of the diaphragm subjected to the greatest strain.

Between the outer edge of the reinforcement 4 and the periphery of the crowned portion 1, is secured a cork or equivalent ring F. This ring is preferably of graduated cross sectional area, decreasing in thickness towards the periphery, and its inner edge 5 overlaps the edge of the reinforcement 4 so that no weakness may develop in this region.

With the construction shown in Figure 2 held in the reproducer frame by means of the usual gaskets T, the offset central portion D' tends to vibrate as a whole, while the bending or flexing takes place in the flat portion, or annulus D² at the outer edge of the diaphragm. That is to say, the vibrating energy is first applied to the center on the cone-shaped central part 3, and then communicated to the larger central or crown portion 1, which, by reason of its substantially conical shape, supported by the reinforcing member 4, is relatively stiff, and therefore resistant. Thus, the movement is communicated to the annulus portion D², which is flat and relatively thin, and although the vibratory effort is applied at the center, the major bending movement takes place in the annulus D², gradually decreasing in the direction of the reinforced central areas.

In connection with the functioning of the above described construction, the cork ring

F of graduated cross section is of much practical importance. Due to the fact that this ring is quite thin at its outer edge and increases in thickness toward its inner edge, and also being elastic, it causes a more gradual, uniform flexing, thereby tending to avoid the formation of partials, and also by reason of its soft nature, tending to further prevent the formation of partials.

By the use of this ring instead of a pad or disk covering the entire central portion, the tendency to muffle the sound is avoided.

It will, of course, be understood that various minor changes may be resorted to in constructing the diaphragm, but in all cases the primary features of making the central portion of the diaphragm offset or bowed, in one form or another, in combination with a reinforcing member 4 and the ring F, of suberous material is preserved to carry into effect the object sought to be attained by the present improvement.

As illustrating the range of such modifications, reference may be had to Figures 3 to 9, inclusive of the drawing, which show varying forms of the central portion of the diaphragm which may be used without departing from the spirit or scope of the invention.

Figures 6, 7, 8 and 9 show more particularly what may be termed a compound offsetting of the central portion D' of the diaphragm, the same being offset to both sides of the plane of the annulus D². That is to say, the central portion D' of the diaphragm D in Figures 6, 7, 8 and 9 is more or less abruptly depressed or offset as indicated at D². This arrangement gives added strength, and serves to better resist the tendency of the diaphragm itself to warp.

From the foregoing it is thought that the features and advantages of the present improvement will be readily apparent to those skilled in the art, and it will of course be understood that further changes in the form, proportion and minor details of construction may be resorted to without departing from the spirit of the invention or scope of the appended claims.

I claim:

1. A construction for reproducer diaphragms comprising a resilient body disk having a central unpadded offset portion and an unpadded outer edge portion, and a ring of suberous material secured to one face of the body disk adjacent the edge of the offset and disposed inside of the unpadded outer edge portion.

2. A construction for reproducer diaphragms comprising a resilient body disk having a central, unpadded offset portion and an unpadded outer edge portion, and a ring of suberous material, having a tapered cross section, secured to one face of the body

disk adjacent the edge of the offset and disposed inside of the unpadded outer edge portion.

3. A construction for reproducer diaphragms comprising a resilient body disk having a central unpadded offset portion and an unpadded outer edge portion, a reinforcing plate secured to said offset portion, and a ring of suberous material secured to

one face of the body disk adjacent the edge 10 of the offset and disposed inside of the unpadded outer edge portion.

In testimony whereof I hereunto affix my signature in the presence of two witnesses.

CHARLES E. SEMPLE, JR.
